(57) CLAIM

The ornamental design for a note dispenser as shown and described.

DESCRIPTION

FIG. 1 is a top front left perspective view of a note dispenser showing the claimed design;

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is a rear view thereof;

FIG. 8 is a bottom front left perspective view thereof; and,

FIG. 9 is a top rear right perspective view thereof.

The broken lines in the figures show portions of the note dispenser that form no part of the claimed design. The line shading is used to show contours.
